DESIGN FOR A CIGARETTE CASE OR SIMILAR ARTICLE

Henry Bogoff, Chicago, Ill., assignor to Rho-Jan,
Chicago, Ill., a copartnership

Application October 25, 1944, Serial No. 115,973

Term of patent 14 years

(Cl. D85—2)

To all whom it may concern:

Be it known that I, Henry Bogoff, a citizen of the United States and resident of Chicago, in the county of Cook and State of Illinois, have invented a new, original, and ornamental Design for a Cigarette Case or Similar Article, of which the following is a specification, reference being had to the accompanying drawing, forming a part thereof.

Fig. 1 is a perspective view of a cigarette case, showing my new design.

Fig. 2 is a top plan view thereof.

Fig. 3 is an end elevational view thereof.

Fig. 4 is a fragmentary sectional detail view taken on line 4—4 of Fig. 2, showing the surface configuration thereof.

The bottom of the cigarette case is plain.

I claim:

The ornamental design for a cigarette case or similar article, substantially as shown and described.

HENRY BOGOFF.
